UNITED STATES PATENT OFFICE.

HERMAN H. KOHLSAAT, OF CHICAGO, ILLINOIS.

PROCESS OF AND MACHINERY FOR DESICCATING SUBSTANCES.

SPECIFICATION forming part of Letters Patent No. 269,684, dated December 26, 1882.

Application filed September 21, 1882. (No model.)

To all whom it may concern:

Be it known that I, HERMAN H. KOHLSAAT, a citizen of the United States, residing at Chicago, in the county of Cook and State of Illinois, have invented certain new and useful Improvements in Process of and Machinery for Desiccating Substances, of which the following specification contains full description.

My invention relates to that class of devices whereby substances more or less glutinous or viscid may be by drying, and with or without mechanical disintegration, reduced to a dry meal or flour in convenient form and suitable condition to be again dissolved and prepared for use by addition of water; and it may be understood by reference to the accompanying drawings, of which—

Figure 1 is an oblique perspective of a machine constructed according to the principle of my invention, having a portion of its case cutaway to disclose certain interior structures. Fig. 2 is a view of one of the drying-cylinders with the canvas jacket removed to show the perforations in the metal shell. Fig. 3 shows details.

25 A is a drying-ease.

B is a trough for containing the liquid to be desiccated.

C is a feed-roller journaled in the cross-bars D, which are pivoted out of sight to the supports a of the case A. The trough B is pivoted at b to the cross-bars D, and by means of the ratchets c and the studs d may be hung at varying height with reference to the feed-roller C, so causing said feed-roller to dip more or less into the liquid which may be contained in the trough B.

E are drying-cylinders extending horizontally within the case A, journaled into the ends 40 of the case A, having their journal-boxes F adjustable vertically, as more fully explained hereinafter.

E' is also a drying-cylinder placed between the feed-roller C and the cylinder E, but fixedly 45 journaled in the ends of the case A. G are pulleys fixed to the axes of the cylinders E and E' outside of the case A.

H is a vertical shaft carrying driving-pulleys I, from which, by means of twist-belts J, motion is communicated to the cylinders E and E'. The shaft H and its pulleys I should be

sustained in suitable bearings, (not shown,) and rotary motion given to it in any usual manner, as by belt K over the pulley L.

M is a pulley fixed on the shaft H, and driving 55 the feed-roller C by means of the belt O, passing over the pulley N, rigidly fixed at the outer end of the axis of said feed-roller. The pulley M has an expanded face to retain its belt O through all the varying positions of the feed-roller C as it is raised and lowered by the cross-bars D.

P is a movable pin, which, being inserted in any one of the holes Q in the supports a of the case A, serves to sustain the cross-bars D, 65 with the feed-roller C and feed-trough B, in any desired position.

R R' are blades notched so as to have square teeth, which are inserted through the slot S in the case A, so that the teeth r may impinge 70 upon the surface of the roller E', the two blades being so placed that the teeth of one are opposite the spaces between the teeth of the other. These blades should be placed a small distance apart, one above the other, as shown, 75 leaving a narrow space between them. They may be rigidly fastened together at any point where the fastening will not obstruct the space, as by rivets through arms T T'. The blades R R' are adjustably fixed in the position 80 described in any convenient manner, as by the arm T extending behind the end of the case A, as shown in the dotted outline T', and adjustably secured thereto by a thumb-bolt, U, through the slot V. The ends T² of the blades 85 R R' should be similarly joined and secured to the adjacent end of the case A. Such joining and fastening is not shown on account of the cutting away of the case A at that end.

W are adjusting-screws oppositely threaded 90 at the two ends, and having central hub to receive a key or wrench, and by their threaded ends entering the body of the journal-boxes F, provided for that purpose with correspondingly female-threaded sockets, and serving to fix and 95 regulate the distance between the adjacent drying-cylinders E E'. The cylinders E and E' are composed of the perforated shell e—preferably of iron or other material which retains heat well—connected by suitable radial planes 100 or spokes to an axis, as shown, and are covered with a jacket or sheathing of canvas or other

similar material. They are so placed in the case A that they may be, when desired, and in the ordinary operation of the apparatus are, in close tangential contact each with those adjacent, and are given a rotary motion in the direction indicated by the arrows.

The case A is somewhat longer in interior dimension than the cylinders E and E', and is closed throughout, except where it terminates 10 below in the lips a², which incline inwardly under and toward the cylinder E', but so as to permit a small segment of that cylinder to protrude downward between the lips a² and receive the contact of the feed-roller C.

15 The inclosed chamber of the case A communicates at any convenient point and in any convenient manner with a warm-air chamber of a furnace, and is thereby maintained at any desired temperature.

20 The feed-roller C is preferably composed of a solid core—or, if hollow, closed at the ends—sheathed in jacket of cotton canvas or similar material.

In operating with this apparatus the trough 25 B is either intermittently or constantly supplied with the liquid to be treated, and, being lifted so that the feed-roller may dip in the liquid to any desired depth, is sustained in that position by the ratchet c engaging with the 30 stud d. The cross-bars D are now raised so as to bring the feed-roller C in contact with the drying-cylinder E'. Motion being now given to the system by power applied to the shaft H, causing it to revolve in the direction indicated by the arrow, the feed-roller C, dipping 35 in the liquid, will carry up a film of it on its rear side to the line of contact with E', which, having at that point a motion in the opposite direction, and being in close contact with the 40 feed-roller, will wipe off the liquid brought up to it by the feed-roller, or some portion of it, and carry it up on its rear side to the line of its own contact with the next roller of the series, which in turn will repeat the operation, 45 so passing it on up to the top cylinder, however many may be employed, which will carry it over to the front side, and by the same process pass it to the next below it, and so on down to cylinder E'. If a sufficiently high de- 50 gree of heat and dryness has been maintained in the drying-case, and a sufficiently long series of drying cylinders been employed to bring the substance being treated to the condition of a thick paste or dough, the blades R and R', 55 being swung into contact with cylinder E', will remove the substance in thin narrow strips of tape-like form, which, sliding down the blades R and R', as down a chute, may be received upon any convenient carrying-surface. I prefer an 60 endless apron of wire-cloth of large mesh, traveling horizontally across the length of the machine—i. e., parallel with the length of the cylinders—at a speed just equal to the circumferential motion of cylinder E', so that the 65 tapes of paste will lie stretched out upon it and not become bunched into a mass, and thence discharged into any suitable drying room or

chamber, or, if sufficiently dry already, into any grinding or disintegrating mill or other apparatus. I have not shown any specific device for thus carrying away the substance from the chute formed by the knives R R'; nor have I shown or described any device for further drying the paste or dough, nor for grinding or disintegrating it, since there are many devices 70 in common use which may be employed for those purposes; and I do not claim any of them as my invention, which is confined to the process which I have described in detail, and to the apparatus shown. 75

It may sometimes be found desirable with some substances to charge the drying-cylinders more heavily than can be done by the single coating in the manner just described, particularly in treating non-fluid substances 80 and those which dry but slowly. In such cases I vary the process by breaking the contact between cylinder E' and the cylinder E following it in the series, which is done by means of the adjusting-screw W, in a manner which will 85 be understood without explanation. Then, swinging the blades R R' away from the cylinder E', I allow it to run in connection with the feed-roller alone for several revolutions, until it becomes sufficiently heavily coated. 90 Then, re-establishing connection with the rest of the series by means of the screws W, the heavy coat obtained on the first cylinder will be transferred to and through the remainder of the series in the same manner as before described. 95

Instead of leaving only the cylinder E' in connection with the feed-roller for the purpose of heavy coating, there may be left two or more of the series, the separation being effected 100 at any desired point by means of the adjusting-screw controlling junction where the separation is to be made. Also, it will sometimes be found to be expedient, after coating the series or any desired portion of it as heavily as desired, to drop the feed-roller out of connection with the drying series, and allow the deposit or coating to make two or more complete circuits before applying the blades to remove it. The series may then be recoated by bringing 105 up the feed-roller again into contact with cylinder E'. The drying will be found to be effected very rapidly, for the reason, first, that, the cylinders being shorter than the case and being hollow, the heated air has access to their 110 inner as well as their outer surface; second, being composed of iron, they will both retain the heat and impart it quickly to the substance applied to them; third, the shell of the cylinders being perforated, the hot air has direct access to the under surface of the canvas sheathing, and through the pores or meshes of that to the liquid itself, so heating and drying it by direct contact on both sides; fourth, the constant transfer of the substance from one 115 cylinder to the next succeeding one constantly exposes new particles and a new surface to the drying effect of the heated air; and, fifth, the mode by which that transfer is effected—viz., 120 125 130 135

friction or rubbing of one canvas surface upon another—generates considerable heat, and of itself tends to dry the substance.

I have found it possible in the desiccation 5 of egg substance (to which I have chiefly applied and for which I have designed this apparatus) to almost complete the desiccation by this friction alone, employing very little additional heat above normal temperature. Further, I find great advantage in the form of the 10 blades R and R', in that by taking off the substance in narrow strips the further drying is effected in much shorter time than when it comes to that stage of the process in large 15 masses, or even small chunks or lumps. As applied to the desiccation of egg, a great advantage is derived by the above structure, in that the use of the feed-roller permits the placing of the feed-trough outside the heated 20 chamber, so that it is not in danger of souring, as is the case when egg substance in bulk is exposed for any considerable time to temperature above the normal, but too low to cook it, as must be done in many forms of apparatus 25 for desiccating eggs. The same advantage will doubtless be found in treating many other substances.

Another feature of my invention which renders it peculiarly effective and easily adaptable 30 to various substances is that the feed-roller can, as in the annexed drawings, be given a higher circumferential motion than the drying-cylinder E', so that while the fluid is in its most fluid state, and so inclined to flow back 35 off the surface of the roller, retrograde motion can be compensated by the more rapid rotation of the roller, so that as much liquid can be brought into contact with the drying-cylinder per unit of its surface as may be desired. 40 Similarly, the first cylinder can be given a speed sufficiently greater than the second, and the second than the third, &c., so that the greater fluidity of the substance in the earlier stages of the process, and its consequently 45 greater retrograde movement, will be met and balanced in each stage by greater movement of the carrying-surface, so insuring uniform thickness and preventing clots and lumps.

I am aware that revolving surfaces of various forms have been employed as drying-surfaces for desiccation of egg and other substance; also, that a cylinder having its curvilinear shell of canvas stretched between rigid heads has been used for such purpose; but I 55 do not claim broadly either the use of the revolving cylindrical surface or the use of the canvas surface; but

What I claim, and desire to secure by Letters Patent, is—

60 1. A desiccating apparatus in which a feed-roller or its equivalent is employed to deposit

the liquid to be desiccated upon the moving drying-surface by contact with such surface, such feed-roller having a circumferential motion at the point or line of contact with such 65 drying-surface in a direction opposite to the motion of the drying-surface at that point or line.

2. In a desiccating apparatus, a feed-roller or its equivalent having for the purpose of 70 feeding the substance to be desiccated to the drying-surface a motion independent of that of such drying-surface.

3. As a drying device in a desiccating apparatus, a heated chamber, in combination with 75 and containing a cylinder open at the ends, and having its curvilinear shell composed of sheet metal or other good conductor of heat, perforated and sheathed in cotton cloth or equivalent woven and porous substance. 80

4. The method and process of desiccating viscid substance, which consists substantially in continuously passing it from one revolving surface to an adjacent one by forcible contact of the two surfaces moving in opposite directions at their points or surfaces of contact. 85

5. The method and process of desiccating substances, which consists substantially in feeding the substance from one moving surface to another by forced contact of such surfaces 90 moving in opposite directions at their points or surfaces of contact within a close chamber or drying-case maintained artificially at a temperature other than normal.

6. As the means of separating the partially-dried substance from the drying-surface of a desiccating apparatus, the blades R and R', or their equivalent, whereby the substance is removed in thin narrow strips or shavings. 95

7. In a desiccating apparatus comprising a 100 series of drying-cylinders over which the substance to be treated is passed, substantially as set forth, the combination, with such cylinders, of means for separating them from contact with each other at any point in the series, and 105 for holding them in contact throughout the whole or any part of the series, substantially as set forth.

8. As the drying-surface of a desiccating apparatus, a series—two or more—of cylinders 110 having their curvilinear surfaces in contact successively—i. e., each with the one following—and having each an independent rotary motion.

And in testimony that I claim the foregoing as 115 my invention I have hereunto set my hand at Chicago, Illinois, this 16th day of September, 1882.

H. H. KOHLSAAT.

In presence of—

J. W. DARNEILLE,
CHAS. S. BURTON.
